UNITED STATES PATENT OFFICE

131,008

DESIGN FOR A CARRYING CASE FOR A STOVE OR SIMILAR ARTICLE

Styles T. Howard, Jeffersonville, Ind.

Application June 4, 1941, Serial No. 101,301

Term of patent 3½ years

To all whom it may concern:

Be it known that I, Styles T. Howard, a citizen of the United States, residing at Jeffersonville, Indiana, have invented a new, original, and ornamental Design for a Carrying Case for a Stove or Similar Article, of which the following is a specification, reference being had to the accompanying drawings forming a part thereof.

Fig. 1 is a perspective view of a carrying case for a stove or similar article showing my new design.

Fig. 2 is a perspective view with the parts folded for transportation.

Fig. 3 is an elevational view showing the side opposite from that shown in Fig. 2.

I claim:

The ornamental design for a carrying case for a stove or similar article, substantially as shown.

STYLES T. HOWARD.
